Attorney

UNITED STATES PATENT OFFICE.

CHARLES JOHN COOKE, OF WASHINGTON, DISTRICT OF COLUMBIA.

REPEATING ATTACHMENT FOR PHONOGRAPHS.

1,373,382.

Specification of Letters Patent. Patented Mar. 29, 1921.

Application filed August 10, 1920. Serial No. 402,548.

To all whom it may concern:

Be it known that I, CHARLES JOHN COOKE, a subject of the King of the United Kingdom of Great Britain and Ireland, residing 5 at Washington, in the District of Columbia, have invented certain new and useful Improvements in Repeating Attachments for Phonographs; and I do hereby declare the following to be a full, clear, and exact description of the invention, such as will enable others skilled in the art to which it 10 pertains to make and use the same.

My invention relates to a repeating mechanism for phonographs, and more especially 15 to means for automatically replaying or successively reproducing a phonographic record indefinitely, within the range of the particular motor employed, and practically without interruption.

20 Phonographs and instruments of like character are extensively employed for the purpose of producing dance music, and in this use obviously it is desirable to repeat the selection indefinitely, and without the 25 interruptions incident to replacing the reproducing needle by hand.

An object of the present invention therefore is to provide a simple, inexpensive, efficient, and self-contained attachment for 30 phonographs, capable of accurately producing the results above indicated.

A further object is the production of an attachment of the character indicated, by 35 agency of which the reproducer is automatically raised each time its needle reaches the end of the record, is instantly and automatically returned to its starting point, and in like manner lowered into operative engagement with the record groove, practically 40 without interruption.

Another object of this invention, when 45 used in connection with phonographs not equipped with automatic stops, is that of preventing what may be termed over-running of the record. That is to say, if an operator is otherwise engaged at the completion of a more or less expensive record, the worst that can happen is merely a return to the starting point, and a partial or 50 complete reproduction of the composition.

A very important feature of this invention is the utilization of the motor driven record itself, as the means of lifting the reproducing needle clear of the record, instantly returning same to its starting point, and then

accurately replacing it in operative contact without the possibility of a scratch or false movement.

The present invention is applicable to sound reproducing machines, generally, 60 herein referred to as phonographs, but by way of exemplification the drawings forming part of this application disclose a machine of the "Victor" type employing horizontally arranged disk records. And, while 65 the primary object of this invention is that of repeating or continuously playing dance music, it is equally applicable to repeating in like manner records of any character.

In the accompanying drawings which 70 form part of this application for Letters Patent, and whereon like characters indicate corresponding parts in the several views:

Fig. 1 is a top plan view of my repeating attachment in position upon a disk record, with its operating arm in retracted normal position, the tone arm and sound box being at starting point upon the record;

Fig. 2 is a fragmentary view also in plan showing the operating arm projected at the 80 instant of delivering the sound box to its outermost or repeating position;

Fig. 3 is a side elevation of the invention showing same at the instant of picking up a sound box for replacement, and also in 85 dotted lines, the sound box as replaced by the end of the operating arm;

Fig. 4 is a top plan view of the invention detached;

Fig. 5 is a vertical central section through 90 parts shown by Fig. 4;

Fig. 6 is a vertical transverse section taken on the zig-zag line 6-6 of Fig. 5;

Fig. 7 is an end view of the outer extremity of operating arm; and

Fig. 8 is a fragmentary view showing in 95 inverted plan the underside of the base plate of attachment.

Reference being had to the drawings and characters thereon, A indicates the top of a 100 phonograph cabinet, B an ordinary phonograph record of the disk type, C the usual power-driven arbor upon which record B is loosely centered, D a tone-arm adapted to sweep over record B in the arc of a circle, 105 and E a vertically movable sound-box or reproducer, pivotally supported as at F by said tone arm, the parts mentioned all being of ordinary and well-known construction.

The invention proper is self-contained and comprises a base plate 10 of relatively thick metal, preferably shaped to substantially conform with the smooth central surface of a phonograph record, and centrally perforated as at 11 to receive the protruding end of an arbor C, as shown by Figs. 3, 5 and 6. Preferably base 10 is die-cast or otherwise formed with a circular cam or cam-track 12 at one side of its center, and with an uprising boss 13 positioned within the center of said cam; also with a second boss 14 rising from the surface of the base plate for purposes which will later appear.

By reference to the cam-track 12 aforesaid it will be seen to include a relatively quick upward incline or cam surface 15 at its front center (Fig. 6), and at a point opposite a reverse or downward incline or cam surface 16 (Fig. 5), while in boss 13 is mounted a vertical stud 17 shouldered and threaded at both ends as best shown by Fig. 5.

Rotatably mounted upon stud 17, and therefore eccentrically positioned, is a turn-block 18, having rearward and lateral extensions 19 to serve as a counterweight, and also a circular, relatively thin, base flange 20, serving as a cover for cam track 12 which it directly surmounts. This turn-block 18 is offset above and below by ordinary washers 21, 21, and is rotatably held in position by agency of a knurled nut 22 threaded upon the upper end of stud 17, and serving also as a convenient means of lifting the attachment.

Pivoted at opposite sides of block 18 by means of a horizontal pivot pin 23, is the inner bifurcated end 24 of a main operating arm 25, which, in the present instance, is shown, in cross section by Fig. 6, as of inverted channel form, and adjustable in length. This adjustability is accomplished by the employment of an outer arm section 26, secured by means of screws 27, 27, and screw holes 28, 28, used selectively according to the degree of extension required. The said two-part adjustable operating arm 25-26, terminates in a rearwardly and downwardly extending working shoe or trailing surface 29, having longitudinal and transverse undercut file teeth 30, constituting a roughened hatched surface for purposing later to appear.

Pivoted horizontally between the opposite sides of lever 25, near its supporting turn-block 18, is a roller-carrying frame 31, having downwardly extending front and rear arms 32, 32 carrying an anti-friction roller or wheel 33, traveling directly upon circular cam-track 12 with stud 17 as its center. The outer end of said bearing frame 31 is provided with an adjusting screw 34, swiveled centrally in the operating arm 25 and sur-

mounted by a knurled head 35, as a means of raising or lowering the outer end of the operating arm. This head 35 is crossed by a strap 36 and is locked in adjusted positions by engagement of said strap when drawn down by agency of a set screw 37 as best shown by Fig. 5.

For the purpose of admitting the said roller or wheel 33, the cam-covering-flange 20 is cut back at its front center as at 38; and, as also shown by Fig. 5, a light spring 39 is located within the confines of the cam-track 12, for the purpose of returning arm 25 to its normal position after each needle-replacing operation.

When in normal position, as shown by Figs. 1, 3, 4 and 5, this operating arm rests against a rubber, or rubber surfaced stop 40, rising from the boss 14 hereinbefore mentioned. And when desired a portion or all of the under surface of base plate 10 may be suitably roughened as shown for example at 41, Fig. 8, to insure additional frictional contact with the central smooth portion of a phonograph record.

The foregoing sets forth one complete embodiment of the present invention, but at the same time it should be understood that I consider myself by no means restricted to the form, arrangement, or combination of parts shown and described. On the contrary these may be variously changed, modified and rearranged without in the least departing from the spirit of the invention, which in a broad sense of the word, comprises an operating or needle replacing arm 100 eccentrically positioned with relation to a phonographic record, the said arm at its outer end being projected in the path of the needle carrying elements at a point approximating the end of a record groove, and 105 means for automatically causing said operating arm to engage said needle carrying element and to replace same at approximately the outermost or repeating position.

The operation of this invention, as embodied in the present illustrations, may be briefly set forth as follows.

Base plate 10 being first centered upon arbor C, by means of its central aperture 11, rests directly upon the surface of record B 115 within the limits of its usual and ordinary reproducing grooves. In this position it will be particularly noted that the main pivot pin or supporting stud 17 is eccentric to the center of rotation of said record B 120 and base plate 10; also that all parts of the repeating attachment normally occupy the position indicated by Figs. 1, 3, 4 and 5.

The phonograph motor (not shown) now being started in the usual manner, base plate 125 10 with all attending parts rotates steadily about arbor C, in the direction indicated by an arrow in the several plan views, the re-

producing needle in the meantime traveling as usual in the spiral record groove toward the center of record B.

At approximately the completion of its travels, a needle-bearing element, such as the sound box E, is automatically conducted into the path of the inclined shoe 29 and is engaged thereby as shown by Fig. 3 of the drawings. The outer extremity 29 of operating arm 25 being thus arrested, further rotation of the attachment instantly throws said arm upon its eccentrically located pivotal support 17, from the position shown by Fig. 1 to that shown by Fig. 2; or, from the normal position shown by full lines in Fig. 3, to the outermost replacing position indicated by dotted lines in said figure, the needle in the meantime having been automatically raised and lowered to avoid scratching over the record.

At the instant of contact between the shoe 29 and a needle-carrying element, such as E, the roller 33 travels up incline 15 thus quickly elevating the outer end 29 of operating arm 25, and consequently the said needle-carrying element, to positively lift the needle out of the record groove and clear of the rotating record. Roller 33 in its raised position then travels upon the horizontal portion of the cam track 12, while the operating arm 25 is being projected as aforesaid by reason of its eccentric pivotal mounting upon stud 17, until reaching its outermost position shown by Fig. 2, whereupon the said roller 33 descending incline 16, causes the needle-carrying element to descend accordingly and lowers the reproducing needle again into operative contact.

Thus lowered the outer extremity of the operating arm is automatically carried beneath the said needle-carrying element and returned by action of spring 39 until arrested by engagement with stop 40, in a position to repeat the operation so long as the phonograph motor keeps the record moving.

Adjustment in length of the operating arm and its attending parts may be readily effected to provide for either ten or twelve inch records by withdrawal and replacement of screws 27; and in elevation is effected, by agency of screw 34, as the means of raising or lowering roller 33 as clearly illustrated by Fig. 5, and when such adjustment has been accomplished said screw may be locked in its adjusted position by agency of strap 36, and set screw 37 by which latter the strap may be drawn into close frictional contact with the knurled head 35 of the adjusting screw.

Having thus described my invention, what I now claim and desire to secure by Letters Patent is:

1. In a phonograph attachment the com-

bination of a supporting base, an arm eccentrically positioned on said base, means co-operating with said arm for automatically lifting a reproducing needle, and means for returning the same to its starting point.

2. In a phonograph attachment the combination of a supporting base, an arm eccentrically positioned on said base, means co-operating with said arm for automatically lifting and lowering a needle, and means for causing said arm to effect a return of said reproducing needle to its starting point.

3. In a phonograph attachment the combination of a supporting base plate, an arm eccentrically positioned on said plate, and means co-operating with said arm for causing it to control a reproducing needle to lift and return the same to its starting point.

4. In a phonograph attachment the combination of a supporting base, an extensible arm eccentrically positioned on said base, and means for causing said arm to control a reproducing needle to automatically return the same to its starting point.

5. In a phonograph attachment the combination of a supporting base, an arm eccentrically positioned on said base, a shoe upon said arm having a roughened surface, and means for causing said arm and shoe to control a reproducing needle to automatically return the same to its starting point.

6. In a phonograph attachment the combination of a supporting base, an arm eccentrically positioned on said base, a shoe upon the free end of said arm having a roughened trailing surface, and means for causing said arm and shoe to control a reproducing needle to automatically return the same to its starting point.

7. In a phonograph attachment the combination of a supporting base, an arm eccentrically positioned on said base, a shoe at the outer end of said arm having a rearwardly declining surface, and means for causing said arm and shoe to control a reproducing needle to automatically return the same to its starting point.

8. In a phonograph attachment the combination of a supporting base, an arm eccentrically mounted on said base, means for regulating the length of said arm, means for regulating the elevation of said arm, and means for causing said arm to control a reproducing needle to automatically return the same to its starting point.

9. In a phonograph attachment the combination of a supporting base, a turn-block eccentrically mounted on said base, an operating arm carried by said block, and means for causing said arm to control a reproducing needle to automatically return the same to its starting point.

10. In a phonograph attachment the com-

bination of a supporting base, a turn-block eccentrically mounted on said base and provided with a counter-balance, an operating arm carried by said block, and means for causing said arm to automatically control a reproducing needle to return the same to its starting point.

11. In a phonograph attachment the combination of a supporting base, a turn-block eccentrically mounted on said base, an operating arm carried by said block and vertically movable with relation thereto, and means for causing said arm to control a reproducing needle to automatically return the same to its starting point.

12. In a phonograph attachment the combination of a supporting base, an operating arm eccentrically pivoted upon said base, means for causing said arm to return a reproducing needle to its starting point, and a cam arranged and adapted to elevate said arm at the beginning of said return movement and to permit of lowering the same at the completion of said movement.

13. In a phonograph attachment the combination of a supporting base, an operating arm eccentrically pivoted upon said base, means for causing said arm to be rotated upon its pivotal connection to return a reproducing needle to its starting point, a cam surface for elevating said arm at the beginning of said return movement, a cam surface to permit said arm to be lowered at the conclusion of said return movement, and

a spring for returning said arm to its normal position.

14. In a phonograph attachment the combination of a supporting base, a cam-track eccentrically positioned upon said base, an operating arm pivotally supported at the center of said cam-track, means for causing said arm to automatically return a reproducing needle to its starting point, and means carried by the arm traveling upon said track whereby the arm is first raised and then lowered during its outward movement, and means for returning all parts to normal positions.

15. In a phonograph attachment the combination of a supporting base having a roughened under surface, an operating arm eccentrically pivoted upon said base, means for causing said arm to automatically return a reproducing needle to its starting point, a cam surface for elevating said arm at the beginning of such return movement, a cam surface for permitting said arm to be lowered at the termination of said return movement, and means for replacing the operating arm in normal position after each replacement of the reproducing needle.

In testimony whereof I affix my signature, in presence of two subscribing witnesses.

CHARLES JOHN COOKE.
